Application filed August 3, 1894. Serial No. 519,378. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of ornamental scrolls of Italian renaissance style arranged as shown in the accompanying drawing. Said scrolls diverge in opposite directions from the center of the design upwardly and are connected at the top by small ornaments and between said ornamental scrolls are placed ornaments of Italian renaissance style as represented in the drawing.

The border or upper portion of the design is formed of ornamental scrolls of Italian re-

naissance style arranged in the form of open panels with ornamental figures hanging by bows of ribbon from said scrolls and ornaments of Italian renaissance style arranged on opposite sides of said ornamental scrolls as shown in the drawing.

What I claim is—

1. The design for wall paper herein shown and described.
2. In the design for wall paper, the border herein shown and described.
